UNITED STATES PATENT OFFICE.

JACOB J. SOUDER, OF WASHINGTON, DISTRICT OF COLUMBIA.

DUMPING-CAR.

SPECIFICATION forming part of Letters Patent No. 371,224, dated October 11, 1887.

Application filed May 3, 1887. Serial No. 237,276. (No model.)

To all whom it may concern:

Be it known that I, JACOB J. SOUDER, a citizen of the United States, residing in Washington, in the District of Columbia, have invented a new and useful Dumping Car, of which the following is a description.

The invention relates to cars of the class which are commonly known as "freight-cars" or as "burden-cars;" and the invention consists in certain novel parts and in certain novel combinations of parts in a car of this character, whereby the car may be used as a "box-car" for the transportation of ordinary miscellaneous package merchandise, and whereby the car may be readily convertible into an automatic or self-discharging car for the conveyance of granular material in bulk, as will be hereinafter specifically described and claimed.

In the drawings, Figure 1 is a top plan view 20 of a car in which my invention is embodied, the roof of the car being removed and the pivoted floor-sections being raised to their vertical or open position. Fig. 2 is a longitudinal vertical section on the line *w w* of Fig. 1. Fig. 25 3 is a transverse vertical section on the line *x x* of Fig. 1, the parts being in adjustment for the discharge of granular material. Fig. 4 is a side elevation of the central exterior portion of the car. Fig. 5 is a top plan, the roof being removed, as in Fig. 1, but showing the floor-sections as closed, and the figure being drawn to a reduced scale. Fig. 6 is a detail vertical section on the line *y y* of Fig. 1, and showing the relation of the covering-shield to 35 the parts which are protected by it. Fig. 7 is a top plan view representing a section of the drop-doors on an enlarged scale. Fig. 8 is a top plan representing a modified form of construction of the pivoted drop-doors or drop-sections.

In the central portion of the car *A*, and hinged, preferably, to the outer longitudinal sills, *a* and *a'*, are the coincident longitudinal floor-sections *A' A'*, which, when in their horizontal position upon the intermediate longitudinal sills, *a² a³ a⁴ a⁵*, constitute the central portion of the floor of the car, and which, when raised to their vertical position, rest against the door-frame *d* and serve as grain-doors to cover 45 the doorways *D*. Near the ends of the car are hinged the end floor-sections, *A³* and *A⁴*, which, in connection with the central sections, *A' A'*, and with the short permanent or fixed end sec-

tions, *A⁵* and *A⁶*, complete the floor of the car as when required for ordinary merchandise. 55

When the car is to be used for the transportation of granular material in bulk, the hinged floor-sections *A' A² A³ A⁴* are raised to their vertical position, uncovering the secondary or grain floor of the car, which, as will be seen, 60 consists of one or more hoppers, *H*, composed, preferably, of metallic sheets, which by their outer edges are attached, by nails or other suitable fastenings, to the bed-frame of the car. The hoppers *H* are each provided with lateral 65 discharge-openings which are closable by doors *h* and *h'*, which are oppositely pivoted by half-hinges *h²* at the central and lowest portion of the hopper. Upon the exterior of the hopper, and extending transversely of the car at 70 either side of the discharge-openings, are attached the triangular hinged chute-wings *I I'*, which are provided with a spring-bolt, *i*, and one of which is provided, also, with a distance or limiting chain, *i'*. 75

A truss bar, *J*, suitably secured to the bed-frame of the car and bearing upon the cross-frame tie-timber or needle-beam *K*, extends longitudinally beneath and along the lowest portion of the hoppers at a point between 80 the two coincident doors *h* and *h'*, and is made of large dimensions to surely meet all the requirements of the situation.

Between the outer longitudinal sills, *a* and *a'*, and the intermediate longitudinal sills, *a²* and *a⁵*, are mounted the drums or windlasses *C* and *C'*, the inner end of the bearing-shaft *c* of which is journaled in bearings upon the intermediate sills, *a³ a⁴*, and the outer extremity of which, projecting through the inner portion of 90 the outer sill, is provided with a squared end, to receive a suitable operating-winch, and with a ratchet wheel, *c¹*, which is secured by a pawl, *c²*, which is pivoted to the car. A suitable cable or rope, *c³*, is attached by one extremity to an eyebolt, *c⁴*, in the under surface of the intermediate sill, *a³* or *a⁴*, and is thence extended downwardly to and through a pulley, *c⁵*, in the door or drop-section *h* or *h'*, thence upwardly to and through a pulley, *c⁶*, in 100 the under surface of the sill *a²* or *a⁵*, thence again downwardly to a pulley, *c⁷*, in the door, thence again upwardly into the traveling pulley *c⁸*, which has movement in both vertical and horizontal planes upon the tie-rod *E* or 105 *E'*, and thence to the drum *C* or *C'*, to which

by its opposite extremity it is securely attached.

A self-closing door or shield, L, is attached to the body of the car by means of hinges l l, 5 and is provided with a spring-bolt, l', which in closing engages a recess, m, which is formed in the sill or in the exterior casing of the car, the whole serving to cover the outer portion of the bearing-shaft c and the ratchet-wheel 10 ic and its pawl, and thus protect this important portion of the operating mechanism against injury through exposure to the weather, and also to secure it against manipulation by unauthorized persons. It will be apparent that 15 if this door or shield L be hinged above the shaft c, as in Fig. 6, it will be closable by its own weight. If its hinge be placed vertically, a spring will be necessary to render it self-closing. The continuous draw-bar N, between 20 the intermediate longitudinal sills, a³ and a⁴, is protected from contact with the granular material contained in this hopper-like receptacle by a tubular inclosing-easing O, which is rigidly secured in position, and which may be 25 composed either of metal, wood, or other suitable material.

When the chute wings I and I' are not required for use, they are swung backward against the body of the hopper, and are secured in this position by the engagement of the spring-bolt i of the wings with the catch j upon the hopper.

It will be noted that when one of the drop sections of the grain receptacle is open it forms, 35 in connection with the opposite section, a continuous inclined plane extending from one side of the car to the other, upon which the grain is directed by the inclination of the end portions of the floor toward the center thereof, so 40 that the entire mass of material is by its own gravity speedily discharged at the desired point upon either side of the car.

It will be seen that both of the two doors or drop-sections h and h' are pivotally connected to a longitudinally-arranged plate, H', which is secured by bolts h⁶ or equivalent means upon the flat upper surface of the truss-bar J. The plate H' is upon each edge provided with a series of knuckles, h³, which alternate with a corresponding series of knuckles, h⁴, which are formed upon the half-hinges h², which, if desired, may themselves be of such dimensions as to constitute the entire door or drop-section. A hinge-pin, h⁵, extending 55 through both series of knuckles from end to end of the drop sections, completes the connection of the parts.

Having described my invention, I claim—

1. A dumping-car for railways, which is 60 provided with a sectional adjustable upper floor for miscellaneous merchandise and with a lower floor for granular material, such lower floor having inwardly-inclined sides and lateral discharge-openings, to which are connected sectional chutes, which, when in use, 65 extend beyond the plane of the track-rails.

2. A dumping-car for railways, which is provided with an upper horizontal floor which comprises pivoted end sections and pivoted side sections, and with a lower hopper-shaped 70 floor which has exterior pivoted wings and pivoted floor-sections, which, in conjunction with the wings, constitute discharge-chutes which extend beyond the exterior vertical line of the track-rails.

3. A dumping-car for railways, which is provided with pivoted floor-sections which are adjustable in a vertical or in a horizontal position, and which, when in place upon the bed-frame of the car, constitute a floor for 80 general merchandise, and which is provided, also, with a hopper-shaped floor underneath the bed-frame for granular material in bulk, such hopper-like floor having oppositely-placed drop-sections, which, when grain is 85 being discharged, constitute an inclined plane which extends across the car downwardly from the outer edge and upper extremity of the closed section to the outer edge of the open section.

4. A dumping-car for railways, which is provided with a receptacle for granular material, the bottom of which is below the bed-frame of the car, and which has pivoted drop-sections which are operated by a raising and lowering mechanism, the shaft of which has 90 its bearings in the bed-frame of the car.

5. The door or drop-section h, pivoted to the lowest portion of the hopper-like floor or receptacle H, and extending, when open, to a 100 point outside the track-rail, in combination with the pivoted adjustable exterior chute-wings, I and I', for the purposes set forth.

6. In a dumping-car for railways, a hopper-like receptacle underneath the bed-frame 105 of the car, and provided with pivoted doors or drop sections, in combination with raising and lowering mechanism, the shaft of which projects to the outside of the car, and with a shield or door which covers and protects such 110 shaft.

7. The combination, with the projecting bearing-shaft c, the ratchet-wheel c³, and the pawl c⁴, of the self-closing covering-shield or door L.

8. The combination, with the truss-bar J, of the longitudinally-arranged plate H', secured to such truss-bar, and the half-hinges h², carrying the doors or drop-sections h h', substantially as described.

9. In a dumping-car for railways, provided with a receptacle for granular material, the floor of which is below the bed-frame of the car, a continuous draw-bar which extends through such receptacle from end to end thereof, and which is provided with a fixed protecting casing.

JACOB J. SOUDER.
